(57) CLAIM

The ornamental design for a tire, as shown and described.

DESCRIPTION

FIG. 1 is a perspective view of a tire taken generally from the front and a first side of the tire;

FIG. 2 is a front view thereof;

FIG. 3 is a side view (first side or second side) thereof;

FIG. 4 is an enlarged partial, perspective view taken generally from the front and the first side thereof;

FIG. 5 is an enlarged, partial front view thereof; and,

FIG. 6 is an enlarged, partial side view (first side or second side) thereof.

The tire interior forms no part of the claim. The tread pattern is understood to repeat throughout the circumference of the tire. The other side view is identical to the illustrated side view.
